AUTOMATIC TAKEUP MECHANISM

William T. Hicks, Glen Rock, and Daniel V. Waters, Lebanon, N. J., assignors to Western Electric Company, Incorporated, New York, N. Y., a corporation of New York

Application September 27, 1951, Serial No. 248,602

14 Claims. (Cl. 242—25)

1

This invention relates to continuous take-up apparatus for material and more particularly to continuous take-up apparatus for insulated wire.

In the manufacture of insulated wire for the communication arts, the take-up mechanisms in most instances require stopping of the machines to cut the wires, remove filled reels, insert empty reels and start the new leading ends of the wires on the empty reels. In certain instances, these steps in the method of manufacturing insulated wires have been aided considerably by a double support for reels so that an empty reel may be readily moved manually into the filling position, while the filled reel is moved into a position for subsequent removal from the machine. However, it has been necessary to stop the machine in order to cut the wire and transfer the new leading end of the wire to the empty reel. This procedure has been satisfactory with various types of insulating material wherein the stopping of the machine will not damage the material or disturb its insulating qualities.

Recently, it has been found desirable to extrude a plastic material on the wires to be embodied in telephone cable. This method of insulating wires for telephone cables opened the field to much higher speed operation with very little manual labor, but to practice this method to the best advantage, a continuous take-up mechanism must be provided. With a continuous take-up mechanism associated with such a method, the scraping of wire due to defective insulation or the interruption of the tubing or extrusion operation, will be eliminated. Furthermore, with automatic cutting means necessary for a continuous take-up, successive reels may be supplied with like lengths of insulated wire to be formed into a cable without the customary splices for short length and scraping of long lengths as in the past.

An object of the present invention is to provide a take-up mechanism which is simple in structure, continuous in operation and highly efficient for taking up continuously advancing material.

With this and other objects in view, the invention comprises a continuous take-up apparatus for a strand including a support with spaced reel supporting units mounted for rotation about an axis intermittently to locate the reel supporting units successively at a filling position. In this apparatus, empty reels moving down a ramp are controlled to locate them singly in a loading position where the successive reel supporting units pick up the empty reels and move

2

them in successive stages relative toward, and eventually into, the filling position. Each reel supporting unit has a power means to drive its reel, the power means in the present embodiment of the invention being an electric motor energized in advance of reaching the filling position, during its stay at the filling position and for a given length of time after leaving the filling position. Furthermore, each reel supporting unit is provided with a fixed position cutter and an element rotatable with the reel, both the cutter and element being positioned out of the normal distributing paths of the strand but adapted to cause cutting of the strand and winding of the new leading end of the strand about an empty reel, moved into the filling position, whenever the strand is moved into general alignment with the cutter and element. A ramp is provided to receive the filled reels after a mechanism has been operated to cause the supporting unit for the filled reel to open, releasing the reel for movement down the ramp.

Other objects and advantages will be apparent from the following detailed description when considered in conjunction with the accompanying drawings wherein:

Fig. 1 is a side elevational view of the apparatus;

Fig. 2 is a view of the other side of the apparatus, portions thereof being broken away;

Fig. 3 is a fragmentary vertical sectional view of one of the reel supporting units and its operating mechanism;

Fig. 4 is a fragmentary detailed view of a portion of the end of the mechanism shown in Fig. 3; and

Fig. 5 is a wiring diagram illustrating the control circuits for the apparatus.

The present embodiment of the apparatus includes a suitable frame 10 for supporting a conventional distributor element 11 carrying spaced pins 12 to straddle a strand of insulated wire 14 to distribute the strand on reels at a filling position. The distributing element and its reciprocating mechanism are not shown in detail as any suitable distributing mechanism may be employed for this purpose.

At the inner portions of its sides, the frame 10 supports annular tracks 15 which have V-shaped peripheries 16 to support grooved rollers 17. The rollers 17 are rotatably supported by pinions 18 mounted at spaced positions on a main support or turret 20. In this embodiment of the invention, the support 20 is hexagonal in

general contour to provide supporting surfaces 21 for six reel supporting units indicated generally at 22.

The reel supporting units are identical in structure and a description of one will apply equally well to all six units. Attention is therefore directed to Fig. 3 which illustrates one of the units as having a bracket 25 mounted on the surface 21 and supporting bearings 26 for a hollow shaft 27. The shaft 27 has a pulley 28 mounted on its outer end, the pulley being driven by belts 29 from its motor 30. A solid shaft 31 extends through the hollow shaft 27 and has a longitudinal groove 30 therein to receive a key 33 of the shaft 27 to permit axial movement of the shaft 31 relative to the shaft 27 and to connect the shafts for rotation one with the other. One end of the shaft 31 carries a bearing supported collar 35 connected to a yoke 36 through pins 37, carried by the yoke and positioned to ride in an annular groove 38 of the collar 35. The yoke 36 is a part of an actuating lever 40 fixed to a shaft 41 which is journaled in a bearing bracket 42 mounted on the surface 21. Another lever 43, having its upper end mounted on the shaft 41, extends downwardly through an aperture 44 in the support 20. A spring 45 having one end connected at 46 to the bracket 45, has its other end connected at 47 to the lever 40 to normally urge the levers 40 and 43 together with the shaft 31 into the positions shown in Fig. 3.

The other end of the shaft 31 is provided with a cone center 50 to enter the adjacent end of the hub of a reel 51. A transfer element 53 mounted on the inner end of the shaft 31 carries a spring press pin 54 positioned to enter an aperture in the adjacent head of the reel to form a positive driving connection between the reel and the shaft 31. The transfer element 53 has its outer end extending around the adjacent head of the reel and provided with a groove 55 adapted to receive and grip the strand 14, should the strand be moved out of its conventional distributing paths.

A cone center 57 to enter the other end of the hub of the reel 51 and to complete the supporting means for the reel, is carried by lever 58 pivotally supported at 59 and having a portion 60 extending through an aperture 61 of the support 20. A spring press plunger 62 supported by the under surface of the support 20 normally urges the lever 58 clockwise into the solid line reel supporting position shown in Fig. 3.

A brake mechanism is provided for each reel supporting unit. The brake mechanism shown in Fig. 3 includes a brake shoe 65 pivotally supported at 66 at one end thereof, while a push rod 67 has its upper end connected at 68 short of the opposite end of the brake shoe 65. The push rod 67 has its lower end connected at 69 to a bell crank lever 70 pivotally supported at 71 by a bracket 72 mounted on the under surface of the support 20. A spring 73 interposed between a bracket 74 and the lever 70 normally holds the brake shoe 65 away from the reel 51. A rod 75, having one end connected to the adjacent arm of the lever 70 at 76, is guided in an aperture 77 in the bracket 74 to maintain its outer end in a given position to be actuated by means hereinafter described.

A transfer arm 80 pivotally supported at 81 intermediate its ends extends through an aperture 82 in the support 20 to have its lower or inner end connected at 83 to a rod 84. A spring 85 normally urges the rod 84 to the right to nor-

mally hold the arm 80 out of the distributing paths of the strand.

The mechanisms for operating the cone centers 50 and 57 into the broken line positions shown in Fig. 3, to discharge a filled reel and to receive an empty reel, include sets of air cylinders 86 and 87 disposed at the unloading and loading positions hereinafter described. The air cylinders 86 and 87 have plungers 88 and 89 positioned to engage and actuate their respective levers 43 and 60. The air cylinders are, in the present embodiment of the invention, mounted in apertures of the tracks 15 and connected in air lines (not shown) under the control of solenoid valves hereinafter described. An air cylinder 90, disposed at the unloading position, has a plunger 91 positioned to engage the rod 75 to actuate the brake 65 moving it against the filled reel to stop rotation of the reel prior to its entering the unloading position. Another air cylinder 93 is mounted at the filling position with its plunger adapted to move the rod 84 to rotate the ram 80 about its pivot to cause the upper portion of the arm to traverse the distributing paths of the wire.

Each reel supporting unit 22 carries a series of brushes 96 included in the electrical circuits of their respective motors 30. These brushes are positioned to move into contact with primary contact strips 97 and secondary contact strips 98 as shown in Fig. 2. The positions of the contact strips are such that the circuits to the motors 30 are completed to energize the motors prior to reaching the filling position, keep them energized during their stay in the filling position and continue energization of the motors at the position beyond the filling position.

The unloading position is indicated at 100 where a ramp 101 is positioned to receive the filled reels when released by the reel supporting units. A cup-shaped receiving end 102 is hinged to the ramp permitting a reel to move past the unloading position if anything should occur to prevent releasing the reel. A photoelectric cell 103 is supported by the frame 10 and included in a circuit with indicating means to indicate whether or not the filled reel is released from the reel supporting unit at the unloading position.

The loading position 105 disposed adjacent the bottom of the apparatus includes a ramp 106 for a supply of empty reels 51. A hinged portion 107 at the lower end of the ramp, serves to locate a reel in general alignment with the cone centers 50 and 57 of the reel supporting units. A photoelectric cell 108 supported by the frame 10 is included in an electric circuit with indicating means to indicate the presence of an empty reel at the loading position.

A mechanism is provided to control all the empty reels by controlling particularly the first and second reels of the supply on the ramp 106. This means includes an arm 110 carried by a lever 111 pivotally supported at 112 and under the control of an air cylinder 114, capable of moving the lever into and out of holding position. An arm 116 carried by a lever 117 pivoted at 112 is under the control of an air cylinder 118 capable of moving the arm into and out of holding position relative to the second reel in the supply. The air cylinders 114 and 118 are operated in a given sequence, under the control of solenoid operated valves, so that after the reel at the loading position has been mounted in the adjacent reel supporting unit and moved free of the ramp 106, the first reel of the supply will be released by

lifting the arm 110, after which the arm will be lowered to receive the next reel released through the raising of the arm 116, which has held all of the other reels of the supply against advancement until the first reel has been released to roll into the loading position.

Each reel supporting unit is equipped with a cutter 115 and a wrapping element 53, which with the arm 80, constitutes the subject matter of a copending application Serial No. 247,524, filed September 20, 1951.

Considering now the operation of the apparatus, attention is directed to the wiring diagram which may be more readily explained by following the successive steps of the operation of the apparatus. The supply lines 119 for the motor circuit are connected to the primary contact strips 97 so that while the brushes 96 of any motor engage the primary contact strips, the motor will be energized. The machine includes two 20 footage counters 120 and 121, referred to hereinafter as the primary and secondary counters. The primary counter is included in a circuit with the top winding of a relay 122 to complete a circuit from a main supply line 123 through the top 25 winding to the other supply line 124 when a given number of feet have been wound on the reel at the filling position. Energization of the top winding of the relay 122 will actuate its contact 125 to complete a circuit through the top winding 126 of a solenoid valve 127. The solenoid valve 127 functions to operate an air cylinder of an indexing mechanism, not shown, this mechanism being the subject matter of a copending application Serial No. 247,524, filed September 20, 1951. The switch shown adjacent the primary footage counter may be actuated during the initial loading of the apparatus with empty reels to index the support 20. A finger 128 movable with the ram of the indexing air cylinder, is positioned to actuate a limit switch 129. It should be understood that the primary footage counter 120 closes its circuit through the top winding of the relay 122 only for a short interval of time sufficient for the indexing mechanism to operate. Once the turret or support 20 has been moved its given distance, the circuit through the top winding of the relay 122 will be open, yet the contact 125 will remain in position to keep the circuit through the top winding 126 of the solenoid valve 127 closed until the bottom winding of the relay 122 is energized through the closing of the switch 129 to return the contact 125 to the position shown in Fig. 5. At this time, the lower winding 130 of the solenoid valve 127 will be energized to cause the air cylinder to return the indexing mechanism to its normal position.

The secondary footage counter 121 is set to close a circuit through the top winding of a relay 132 when the reel recently moved from the filling position has been filled with the desired amount of wire. Energization of the top winding of the relay 132 will operate its contact 133 to complete a circuit through the top winding 134 of a solenoid valve 135. The energization of the solenoid valve will cause operation of the air cylinder 93, Fig. 2, to move the arm 80 from its position in Fig. 3 about its pivot 81 to move the strand or wire 14, regardless of its distributed path, into general alignment with the adjacent cutter 115 and transfer element 53. While the wire is in this position, it will be received in the groove 55 in the transfer element, forced past the cutter 115 to cut the wire leaving the trailing end to wind up on the filled reel, and winding the 75

new leading end about the empty reel previously moved into the filling position. A limit switch 136, positioned to be operated by the arm 80 or its actuating mechanism after completing its movement across the distributing paths of the wire is operated to complete a circuit through the bottom winding of the relay 132 to return the contact 133 to its normal position shown in Fig. 5 to complete a circuit through the bottom winding 139 of the solenoid valve 135 to return the air cylinder to its normal position. The secondary footage counter 121 closes the circuit through the top winding of the relay 132 and retains this condition a length of time sufficient for the operation of the arm 80 by energizing the top winding prior to the energization of the bottom winding through the closing of the limit switch 136.

When the reel is moved from the filling position to the next position, a timing unit 140 is energized through the operation of the contact 133 during energization of the top winding of the relay 132. Energization of the timing unit 140 will operate its contact 141 to close a circuit through a relay 142 to close its bottom contacts to complete a circuit from the supply lines 119 to the motor whose brushes contact the secondary contact strips 98. This motor circuit remains closed for a given length of time determined by the setting of the timing unit 140.

During energization of the relay 142 its top contact is operated to open a circuit to the top winding of a relay 144 and close a circuit to a timing unit 145. In timing-in the contact 146 is operated to close a circuit through the bottom winding of the relay 144 operating its contact to complete a circuit through the bottom winding 147 of a solenoid valve 148 to operate the air cylinder 90, Fig. 3, to move the brake 65 into engagement with the filled reel. The brake is applied for a given length of time determined by the setting of the timing unit 145 and when this unit times-out, which is subsequent to the timing-out of the unit 140 and the de-energization of the relay 142 and the bottom winding of the relay 144, the top winding of the relay 144 is energized to return its contact to the normal position to de-energize the bottom winding 147 of the solenoid valve 148 and energize the top winding 149 thereof. This operation returns the brake 65 to its normal position.

The timing unit 145 also controls the operation of a relay 152 for the unloading and loading mechanisms. Normally, the bottom winding of this relay is energized, energizing the bottom windings of solenoid valves 153, 154, 155 and 156. The solenoid valves 153 and 154 are in air lines to the air cylinders 86 and 87 at the unloading position, while the solenoid valves 155 and 156 are in air lines to the air cylinders 88 and 89 at the loading position. Therefore, the air cylinders 86 and 87 are supplied with air under pressure to hold the plungers 83 and 89 normally out of the paths of the levers 43 and 60 until given time intervals controlled by the timing unit 145 when the solenoids 153 to 156, inclusive, will have their bottom windings de-energized and their top windings energized through the operation of the contact during energization of the bottom winding of the relay 152. Therefore, a filled reel will be released at the unloading position and a reel supporting unit opened to receive an empty reel at the loading position.

During energization of the top windings of solenoid valves 153 to 156, inclusive, for the nor-

mal functions of the unloading and loading means, circuits are completed through lamps 160 and 161 disposed at the opposite side of the support 20 from their light sensitive elements 103 and 108 at the unloading position 109 and the loading position 105. The light sensitive elements 103 and 108 are provided with a 110 volt direct current supply from a transformer 163. The lamps 160 and 161 are under the control of the timing units so that they will be energized only during certain intervals of the intermittent operating cycles of the apparatus. In other words, the lamp 160 is energized after the filled reel has moved into the unloading position and the top winding of the relay 152 has been energized to complete circuits through the top windings of the solenoid valves 153 to 156, inclusive. During this interval of time, before the timing unit 145 times-out and after the completion of the time required for unloading the filled reel, a circuit through the normally closed bottom contact of a relay 164 will be completed through a visual signal 165 and an audible signal 166 if the relay 164 is not energized to open this circuit. This occurs when a filled reel fails to leave the unloading position. If the filled reel has been released successfully from the reel supporting unit at the unloading position and rolled down the ramp 101, the light ray from the lamp 160 will have actuated the element 103 to complete a circuit through the relay 164 to energize it, operating its contacts to open the circuit through the signals 165 and 166 prior to the timing out of the unit 145. However, if a reel should be jammed or otherwise fail to leave the reel supporting unit at the unloading position during the interval of rest of the support 20, the filled reel at this position, will interrupt the light ray from the lamp 160 preventing its action on the element 103 and as a result, the relay 164 will not be energized allowing its bottom contact to complete a circuit through the signals warning the operator so that the filled reel may be removed manually at the unloading position.

The loading mechanism is so arranged that during the interval of rest after a reel has been received by the reel supporting unit at the loading position and moved to the next position, the leading reel of the supply will be released through operation of the air cylinder 114, Fig. 2, to raise the arm 110 through the rocking of the lever 111. The air cylinder 114 is under the control of a solenoid valve 168, the bottom winding of which is normally closed through the energization of the bottom winding of a relay 169. The bottom winding of the relay 169 is in a circuit completed through the energization of the bottom winding of the relay 144. However, the top winding of the relay 169 is in a circuit under the control of the contact 133 of the relay 132, the circuit of which is completed by the energization of the top winding of the relay 132 as a result of the operation of the secondary footage counter 121. As a result of these circuit elements, the moment the secondary footage counter operates to complete the circuit of the top winding of the relay 132, the top winding of the relay 169 is energized operating the contact to complete circuit through the top winding of the solenoid valve 168 to operate the air cylinder 114 to release the leading empty reel so that it may roll down the ramp 106 to the loading position 105.

A relay 170 has its top winding included in the circuit controlling the bottom winding of the relay 169, so that the air cylinder 118 will move its lever 117 upwardly while the air cyl-

inder 114 is moved downwardly moving the arm 110 into position to stop the next leading reel of the supply when released by the arm 116. Energization of the top winding of the relay 170 will operate its contact to energize the top winding of a solenoid valve 171, controlling the air cylinder 118. The bottom winding of the relay 170 is under the control of the timing unit 145 causing operation of the relay contact to open the circuit to the top winding of the solenoid valve 171 and close the circuit to the bottom winding thereof, resulting in the operation of the air cylinder 118 to move the arm 116 downwardly to hold the reels of the supply on the ramp back of the first or leading reel. The bottom winding of the relay 170 is also under the control of the normally open top contact of the relay 164 to hold the reels of the supply on the ramp during disturbance in the unloading of a filled reel.

The lamp 161 is in a circuit under the control of the timing unit 145 so that it will be illuminated during an interval of time when an empty reel should be located at the loading position ready to be received during the next intermittent movement of the support 20. If there should be an empty reel at the loading position, this empty reel will interrupt the ray of light from the lamp 161 to the light sensitive element 108. However, if there should be no empty reel at the loading position during this interval of time when the lamp is energized, the ray of light directed to the element 108 will cause the element to function to complete a circuit through a relay 174 causing it, when energized, to close its contact 175 to complete a circuit through a visual signal 176 and an audible signal 177. The signal circuits for the loading and unloading positions include locking relays 178 and 179 so that once the disturbing condition exists at either the loading or unloading position, the signals will remain energized until the operator recognizes the condition, at which time switches 180 and 181 may be actuated to open the signal circuits.

After the apparatus has been provided with a supply of empty reels on the ramp 106 and in the various stations from the loading position to the filling position and after the leading end of the strand or insulated wire is tied to the reel at the filling position, the apparatus may be set in motion. The reel at the filling position is driven through the energization of its motor to wind the wire on the reel during the actuation of the distributor 11 to uniformly distribute a strand on the reel. This operation continues until a pre-determined number of feet of wire has been wound on the reel determined by the primary footage counter 120. At that time, the indexing mechanism is set in motion to index the support one position, moving the substantially filled reel to the next position and bringing an empty reel to the filling position. When the desired number of feet of wire has been wound on the reel, determined by the secondary footage counter 121, this winding operation continuing after the indexing of the support, the air cylinder 93 is operated to move the arm 80 to transfer the wire regardless of its distributing path into general alignment with cutter 115 and the transfer arm 53 at the filling position. As a result of this operation, the wire will be severed allowing the trailing end from the cut portion to wind onto the filled reel while the transfer arm 53, having received the wire in the notch 55 thereof, will wind the new leading end of the wire about

the empty reel at the filling position. Subsequent to this operation, the air cylinder 90 will be operated to actuate the brake 65 moving it into engagement with the filled reel to stop rotation thereof. The motor 30 at this position has been de-energized allowing the brake 65 to function to stop the reel prior to its movement into the unloading position. These operations continue through the intermittent moving and rest periods of the support providing a continuous take-up for the wire or strand material, depositing the filled reels on the ramp 101 and successively picking up empty reels at the loading position.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. In a continuous take-up apparatus for a strand, a support mounted on an axis, reel supporting units mounted at spaced positions on the support and having pairs of centers adapted to engage the hubs of reels and rotatably support the reels, means to rotate the support intermittently to successively locate the reel supporting units at a filling position, means to supply empty reels to a loading position, and means energizable to operate the reel supporting units adjacent the loading position to cause their centers to enter the hubs and rotatably support the reels singly at the loading position.

2. In a continuous take-up apparatus for a strand, a support mounted on an axis, reel supporting units mounted at spaced positions on the support and having pairs of centers adapted to engage the hubs of reels and rotatably support the reels, means to rotate the support intermittently to successively locate the reel supporting units at a filling position, means to supply empty reels to a loading position, and means energizable to operate the reel supporting units adjacent the loading position to cause their centers to enter the hubs and rotatably support the reels singly at the loading position, indicating means, and means energizable by the absence of a reel at the loading position to operate the indicating means.

3. In a continuous take-up apparatus for a strand, a support mounted on an axis, reel supporting units mounted at spaced positions on the support and having pairs of centers adapted to engage the hubs of reels and rotatably support the reels, means to rotate the support intermittently to successively locate the reel supporting units at a filling position, a ramp for a supply of empty reels extending to a loading position adjacent the support whereby the reels may roll singly to the loading position, means to hold the leading reel of the supply against forward movement and operable to release the leading reel after the reel at the loading position has been removed from the ramp, and means energizable to operate the reel supporting units adjacent the loading position to cause their centers to enter the hubs and rotatably support the reels singly at the loading position.

4. In a continuous take-up apparatus for a strand, a support mounted on an axis, reel supporting units mounted at spaced positions on the support and having pairs of centers adapted to engage the hubs of the reels and rotatably support the reels, means to rotate the support inter-

mittently to successively locate the reel supporting units at a filling position, a ramp for a supply of empty reels extending to a loading position adjacent the support whereby the reels may roll singly to the loading position, means to hold the leading reel of the supply against forward movement and operable to release the leading reel after the reel at the loading position has been removed from the ramp, means energizable to operate the reel supporting units adjacent the loading position to cause their centers to enter the hubs and rotatably support the reels singly at the loading position, and a swingable member disposed at the lower end of the ramp to locate the reels singly at the loading position and movable by the reels as they are moved with the supporting units during intermittent rotation of the support.

5. In a continuous take-up apparatus for a strand, a support mounted on an axis, reel supporting units mounted at spaced positions on the support and having pairs of centers adapted to engage the hubs of the reels and rotatably support the reels, means to rotate the support intermittently to successively locate the reel supporting units at a filling position, a ramp for a supply of empty reels extending to a loading position adjacent the support whereby the reels may roll singly to the loading position, a first holding element, normally holding the first reel of the supply during the presence of the reel in the loading position, actuatable to free the said first reel after the reel at the loading position is removed from the ramp, a second holding element, normally holding the second and other following reels of the supply against advancement, actuatable to release its reel subsequent to the first holding element returning to its normal position after releasing the said first reel, and means energizable to operate the reel supporting units adjacent the loading position to cause their centers to enter the hubs and rotatably support the reels singly at the loading position.

6. In a continuous take-up apparatus for a strand, a support mounted on an axis, reel supporting units mounted at spaced positions on the support and having pairs of centers adapted to engage the hubs of the reels and rotatably support the reels, means to rotate the support intermittently to successively locate the reel supporting units at a filling position, means to supply empty reels to a loading position, and means energizable to operate the reel supporting units adjacent the loading position to cause their centers to enter the hubs and rotatably support the reels singly at the loading position, and a photo-electric cell, in a circuit with energizable indicating means, energizable to indicate the absence of a reel at the loading position.

7. In a continuous take-up apparatus for a strand, a support mounted on an axis, reel supporting units mounted at spaced positions about the support and including sets of centers normally urged into positions to engage the hubs of the reels and rotatably support reels, means to rotate the support intermittently to successively locate the reel supporting units at a filling position, means to supply empty reels to a loading position, and means to cause relative movement of the centers adjacent the loading position to cause them to enter the hubs of the reels singly disposed at that position.

8. In a continuous take-up apparatus for a strand, a support mounted on an axis, reel supporting units mounted at spaced positions on the

support and having pairs of centers adapted to engage the hubs of the reels and rotatably support the reels, power means for each unit energizable to rotate one of the centers to rotate its reel, means energizable to rotate the support intermittently to successively locate the units with their reels in a filling position, and means to energize the power means prior to and during the location of each unit with its reel in the filling position.

9. In a continuous take-up apparatus for a strand, a support mounted on an axis, reel supporting units mounted at spaced positions on the support and having pairs of centers adapted to engage the hubs of the reels and rotatably support the reels, power means for each unit energizable to rotate one of the centers to rotate its reel, means energizable to rotate the support intermittently to successively locate the units with their reels in a filling position, means to energize the power means prior to and during the location of each unit with its reel in the filling position, and means to energize the rotating means for the support when the reel at the loading position is approximately filled with the strand to rotate the support one step.

10. In a continuous take-up apparatus for a strand, a support mounted on an axis, reel supporting units mounted at spaced positions on the support and having pairs of centers adapted to engage the hubs of the reels and rotatably support the reels, power means for each unit energizable to rotate one of the centers to rotate its reel, means energizable to rotate the support intermittently to successively locate the units with their reels in a filling position, means to energize the power means prior to and during the location of each unit with its reel in the filling position, means to energize the rotating means for the support when the reel at the loading position is approximately filled with the strand to rotate the support one step, and means to cut the strand, and means to continue energization of the power means for the filled reel beyond the filling position to cause winding of the trailing end of the strand on the filled reel.

11. In a continuous take-up apparatus for a strand, a support mounted on an axis, reel supporting units mounted at spaced positions on the support and having pairs of centers adapted to engage the hubs of the reels and rotatably support the reels, power means for each unit energizable to drive its reel, means energizable to rotate the support intermittently to successively locate the units with their reels in a filling position, means to distribute a strand on the reels when located at the filling position, means to energize the power means prior to and during the location of each unit with its reel in the filling position, means to energize the rotating means for the support when the reel at the loading position is approximately filled with the strand to rotate the support one step, means to cut the strand, and means to connect the new leading end of the strand to the rotating empty reel moved into the filling position.

12. In a continuous take-up apparatus for a strand, a support mounted on an axis, reel supporting units mounted at spaced positions on the support and having pairs of centers adapted to engage the hubs of the reels and rotatably support the reels, power means for each unit energizable to drive its reel to wind a strand thereon, means energizable to rotate the support intermittently to successively locate the units with

75

their reels in a filling position, means to energize the power means prior to and during the location of each unit with its reel in the filling position, means to distribute the strand on the reel, means to energize the rotating means for the support when the reel at the loading position is approximately filled with the strand to rotate the support one step, means to cut the strand, and means to grip the new leading end of the strand and wrap it about the rotating empty reel moved into the filling position.

13. In a continuous take-up apparatus for a strand, a support mounted on an axis, reel supporting units mounted at spaced positions on the support and having pairs of centers adapted to engage the hubs of the reels and rotatably support the reels, power means for each unit energizable to drive its reel and wind a strand thereon, means energizable to rotate the support intermittently to successively locate the units with their reels in a filling position, means to energize the power means prior to and during the location of each unit with its reel in the filling position, means to distribute the strand on the reel, means to energize the rotating means for the support when the reel at the loading position is approximately filled with the strand to rotate the support one step, and means to cut the strand, means to continue energization of the power means for the filled reel beyond the filling position to cause winding of the trailing end of the strand on the filled reel, a ramp disposed at an unloading position, and means to cause relative movement of the centers at the unloading position to free the filled reels for rolling movement down the unloading ramp.

14. In a continuous take-up apparatus for a strand, a support mounted on an axis, reel supporting units mounted at spaced positions on the support and having pairs of centers adapted to engage the hubs of the reels and rotatably support the reels, power means for each unit energizable to drive its reel, means energizable to rotate the support intermittently to successively locate the units with their reels in a filling position, means to energize the power means prior to and during the location of each unit with its reel in the filling position, means to distribute the strand on the reel, means to energize the rotating means for the support when the reel at the loading position is approximately filled with the strand to rotate the support one step, means to cut the strand, means to continue energization of the power means for the filled reel beyond the filling position to cause winding of the trailing end of the strand on the filled reel, a ramp disposed at an unloading position, means to cause relative movement of the centers at the unloading position to free the filled reels for movement down the unloading ramp, indicating means, and means energizable to operate the indicating means should a filled reel fail to be freed at the unloading position.
